US00D757048S

(12) **United States Design Patent**
Ralphs et al.

(10) **Patent No.:** **US D757,048 S**
(45) **Date of Patent:** **** May 24, 2016**

(54) **DISPLAY SCREEN WITH GRAPHICAL USER INTERFACE**

(71) Applicant: **Microsoft Corporation**, Redmond, WA (US)

(72) Inventors: **Brian Ralphs**, Redmond, WA (US); **Benjamin Perry**, Redmond, WA (US); **Xiaojie Chen**, Seattle, WA (US)

(73) Assignee: **Microsoft Corporation**, Redmond, WA (US)

(**) Term: **14 Years**

(21) Appl. No.: **29/501,161**

(22) Filed: **Sep. 2, 2014**

(51) LOC (10) Cl. **14-04**

(52) U.S. Cl.

USPC **D14/485**

(58) **Field of Classification Search**

USPC **D14/485-495**

CPC **G06F 3/0481; G06F**

2203/04803-2203/04805; G06F 17/24; G06F

17/30056; H04N 1/00193; H04N 21/234336

See application file for complete search history.

(57) **CLAIM**

The ornamental design for a display screen with graphical user interface, as shown and described.

DESCRIPTION

The FIGURE is a front view of a display screen with graphical user interface showing my/our new design.

The broken line showing of the remainder of the user interface and the remainder of the display screen is for environmental purposes only and forms no part of the claimed design.

1 Claim, 1 Drawing Sheet
